DISPENSING SPOUT CLOSURE FOR
METALLIC RECEPTACLES

Isidor Newman, New York, N. Y.

Application April 16, 1934, Serial No. 720,901

5 Claims. (Cl. 221—11)

My present invention, which relates generally to metallic receptacles, has particular reference to a receptacle having a pouring spout which receptacle, until it be desired to use the contents thereof, is sealed by a frangible seal, preferably of the kind described in my Letters Patent No. 1,805,003 issued May 12, 1931.

Generically the invention resides in designing the spout to receive a plug-like member of tubular form which serves as a closure for the opening of the receptacle and as a control valve for regulating the dispensing of the receptacle's contents.

More specifically the invention comprises a cap having a cylindrical skirt to serve as a plug for the spout cup, there being a skirt wall to cooperate with the entrant end of the spout's lip, the skirt (preferably below the opening) being split to provide resilient means frictionally to hold the valve member in place.

Other objects will in part be obvious and in part be pointed out hereinafter.

To the attainment of the aforesaid objects and ends, the invention still further resides in the novel details of construction, combination and arrangement of parts, all of which will be first fully described in the following detailed description, then be particularly pointed out in the appended claims, reference being had to the accompanying drawing in which:

Figure 1 is a perspective view of a portion of a can with my invention applied, the valve member being in the "open" position.

Figure 2 is a detail vertical section showing the valve member in the "closed" position and the frangible seal unbroken.

Figure 3 is a view similar to Figure 2 but with the seal fractured and with the valve open.

Figure 4 is a view similar to Figure 2 with the several parts separated.

Figure 5 is a detail perspective view of the valve member per se.

Figure 6 is a detail horizontal section on the line 6—6 of Figure 3.

Figure 7 is a detail vertical section hereinafter referred to.

Referring now to the accompanying drawing in which like numerals and letters of reference indicate like parts in all the figures, 1 represents the receptacle and 2 its top, the latter having an opening surrounded by an upstanding flange 3 over which is fitted the sealing cup-like cap 4. The cap 4 has an upstanding annulus turned over as at 5 to fit over the flange 3 and to be rolled into tight engagement therewith so as

to hold the cap 4 fixedly to the flange 3. The cap or sealing member 4 has a scored line similar to the line 17 in my Patent No. 1,805,003 aforesaid in order to provide a disk 13 which may be separated from the cap along the scoring line, by pressing down on the disk 13 with a suitable tool or implement engaged in the depression 14.

The spout member comprises a cup-like body 6 which fits snugly within the cap 4 and is held in place with retaining friction (Figures 2 and 3) or by rolling a bead in the flange 3, cap annulus and cup 6 (Figure 7). The spout member also includes the lip or spout proper 8. The spout cup 6 has a hole 7 in its bottom which preferably corresponds in area to that in the can top, left by the punched-in disk 13.

In Figure 5 is shown (in perspective) the plug-like valve member which includes a cylindrical skirt 10 having a laterally elongated opening 11 to correspond to the entrant end of the spout 8. The skirt is slotted as at 12 to provide resilient fingers 15 which may be expanded slightly so that when the skirt is fitted into the cup 6 it will be held there by retaining friction. The valve member also includes a crown-like top 9 whose edge may be indented or roughened as at 16 to afford a non-slip gripping surface for the fingers.

After punching in the disk 13 and replacing the valve member it may be turned to the position shown in Figure 2 for the purpose of closing the outlet, or it may be moved to the position shown in Figure 3 in order to open the same.

In this embodiment of my invention I prefer to fit the spout to the can so that it may be immovably positioned thereon, although if preferred it may be swivelly secured.

In Figure 7 those parts which correspond to similar parts in the preceding figures bear the same reference numeral plus the index letter "a". In this figure the bead is indicated by 17.

While I have shown and described the preferred embodiments of my invention it will be obvious to those skilled in the art that changes in the details of construction and design of parts may be made without departing from the spirit of the invention and the scope of the appended claims.

What I claim is:

1. A receptacle having a spout with a lip and a cup-like portion that has a suitable opening for communicating with the interior of the receptacle, a rotatable valve member having a skirt provided with an outlet to register upon rotation of the valve with the inlet end of the lip of the spout, and means to hold the skirt in said cup-like portion by retaining friction while permitting

its being rotated to bring the outlet in to or out of register with said lip, said means comprising a slit in the skirt intersecting with the outlet of the skirt whereby to provide a pair of oppositely projecting spring fingers constantly to engage the cup-like portion of the spout.

2. A receptacle having a spout with a lip and a cup-like portion that has a suitable opening for communicating with the interior of the receptacle, and a rotatable valve member having a skirt provided with an outlet to register upon rotation of the valve with the inlet end of the lip of the spout, said skirt having a split portion to provide expandible fingers for holding the valve member in place in said cup-like portion.

3. A receptacle having a spout with a lip and a cup-like portion that has a suitable opening for communicating with the interior of the receptacle and a rotatable valve member having a skirt provided with an outlet to register upon rotation of the valve with the inlet end of the lip of the spout, said skirt, below said outlet, having a split portion to provide expandible fingers for holding the valve member in place in said cup-like portion.

4. A receptacle having a spout with a lip and a

cup-like portion that has a suitable opening for communicating with the interior of the receptacle, a tubular rotatable valve member to fit in said cup-like portion over the opening therein and having a port in its tubular portion to register upon rotation of the valve with the entrance to said lip when said valve is in one position and to be closed by said cup-like portion when said valve is in another position, and means removably and rotatably to hold said valve member in place by friction.

5. A receptacle having a spout with a lip and a cup-like portion that has a suitable opening for communicating with the interior of the receptacle, a tubular rotatable valve member to fit in said cup-like portion over the opening therein and having a port in its tubular portion to register upon rotation of the valve with the entrance to said lip when said valve is in one position and to be closed by said cup-like portion when said valve is in another position, and means removably and rotatably to hold said valve member in place by friction, said last-named means comprising resilient fingers.

ISIDOR NEWMAN. 25
